Primary Examiner — Philip S Hyder*Assistant Examiner* — Roselynne Cody*(74) Attorney, Agent, or Firm* — Young & Thompson**CLAIM**

The ornamental design for a cutting tool, as shown and described.

DESCRIPTION

FIG. 1 is a top view of the cutting tool.

FIG. 2 is a bottom view thereof.

FIG. 3 is a side view thereof.

FIG. 4 is an opposite side view thereof.

FIG. 5 is a front view thereof;

FIG. 6 is a rear view thereof; and,

FIG. 7 is a bottom perspective view thereof.

The broken lines in FIG. 1 illustrate features of the cutting tool that form no part of the claim.
